UNITED STATES PATENT OFFICE

2,574,308

MULTIPLE POLE SWITCH FOR TARIFF CLOCKS

Ernst Widmer, Oberwil-Zug, Switzerland, assignor to Landis & Gyr, A. G., Zug, Switzerland, a body corporate of Switzerland

Application February 4, 1948, Serial No. 6,332
In Switzerland February 15, 1940

Section 1, Public Law 690, August 8, 1946
Patent expires February 15, 1960

1 Claim. (Cl. 200—6)

1

The present invention relates to an improved multiple pole switch such as may be used, for instance, with tariff clocks, time switches, and the like.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate an embodiment of the invention, and together with the description, serve to explain the principles of the invention.

The invention has for its object the provision of a multiple pole switch capable of handling large outputs but of compact shape and design. Another object is the provision of a multiple pole switch the movable contacts of which are mounted for movement by a single cam element in a plane substantially perpendicular to the axis of the cam element and toward and away from said axis.

Of the drawings:

Fig. 1 is a plan view with certain parts broken away of a typical and illustrative embodiment of the switch of the invention shown in use with a clock switch, only so much of the latter being shown as is necessary for an understanding of the invention; and,

Fig. 2 is a cross-sectional view taken along line 2—2 of Fig. 1.

As shown in the drawing, a switch disc 1 of the switch is, as usual, provided with switching pins 2 which act on a switch star wheel 3. The switch star wheel 3 coacts, by means which are conventional and therefore not shown, with the nose pieces 4 of a conventional release device 5, 6. 5 is a disc which carries the nose pieces 4 and which is firmly fixed on a spindle 7 carrying a cam 8 formed of insulating material. 6 is a housing or case for a spring which is in working connection on the one hand with the disc 5 and on the other hand through a gearing 9 with the axis of the switch disc 1.

The cam 8 has three arms, corresponding in number to the number of contact members or poles, and is located in a recess of a member 10 of insulating material. This member 10 of insulating material serves as the carrier member of

the switch and by the external walls 11 thereof and by internal walls 12, three chambers are formed therein.

Into each of these chambers there project, in grooves arranged in the base thereof, two current-carrying strips 13, 14 bent upwardly at their inner ends. Each strip 13 carries at its bent end a contact 15 forming the fixed pole of a contact member. When the switch is closed there rests against each contact 15 a contact 16 forming the movable pole of the contact member. Each contact 16 is carried at the free end of a leaf spring 17 which is curved or bent in hooked form and is fixed to the bent-up end of the strip 14. Thin strips 18 of copper connected to the leaf spring 17 on the strip 14 or with the contact 16 ensure a good conduction of current from the strip 14 to the contact 16. Between each contact 16 and its copper strip 18 there is also fixed an angularly bent metal strip 19, the free end of which projects into the path of movement of the arms of the cam 8.

The member 10 of insulating material may be closed at its top by a cover of insulating material, not shown, which can be fixed by means of screws fitted in screw holes 20 in the member 10.

In operation the spring in the housing or case 6 is tensioned through the gearing 9. When a switching pin 2 comes into contact with an arm of the switch star wheel 3 it rotates this wheel until it is clear of the said arm and thus the switch star wheel brings the release device 5, 6 into operation so that the cam 8 is freed for a partial rotation and raises the outer ends of the metal strips 19. In this way the movable contacts 16 are moved away from the fixed contacts 15, i. e., the switch is opened. When the next switching pin 2 engages the switch star wheel 3 the cam 8 again undergoes a partial rotation and moves clear of the ends of the metal strips 19 which are enabled to move to the position shown in full lines in Figure 1, whereby the movable contacts 16 are carried in the paths directed towards the spindle or switch axis 7 and the switch is again closed.

The arrangement of the paths of the movable pole parts of a switch in a common plane intersecting perpendicularly the axis of the switch and all the movable contacts or pole parts being controlled by a single cam, permits of constructing a switch for a large output (30—50A) of small constructional dimensions, in particular the width, which with the known switches, must be large owing to the arrangement of cams in alignment for the separate movable contacts.

A different form of construction from that shown can be used. Thus, the movable contacts could be arranged on levers which lie adjacent to each other in a plane perpendicular to the switch axis and each of which is raised by one stage of the common cam.

With the embodiment shown the result is attained that the constructional dimensions can be kept very small both in height and depth, since the movable contacts are arranged in star form about the switch axis 7. The internal partition walls 12 with lateral projections 12a thereof offer good protection both against flashing-over and against surface leakage currents.

The invention is not limited to a triple pole construction as described and shown for the poles can be as many as desired, and the switch could also be, for example a double-pole one.

The invention in its broader aspects is not limited to the specific mechanisms shown and described but departures may be made therefrom, within the scope of the accompanying claim, without departing from the principles of the invention and without sacrificing its chief advantages.

What is claimed is:

An electrical switch comprising, in combination, an insulated base member having side walls and a central chamber, a cam element in the chamber rotatable about an axis, three sets of cooperating stationary and movable contacts

symmetrically arranged in said chamber about said axis, a plurality of reentrant walls integral with the side walls of said base member and extending into said chamber adjacent respective ones of said sets of contacts, said reentrant walls each interrupting straight line communication between its adjacent set of contacts and the other sets of contacts and cam element, a curved leaf spring for each movable contact mounting said contacts for movement in a plane substantially perpendicular to the axis of said cam element, said springs being arranged to curve about said reentrant walls, and curved engagement members one secured to each movable contact, curved about a said reentrant wall and having an end adjacent said cam element for engagement thereby to actuate said movable contacts.
